[57] CLAIM

The ornamental design for a baking oven lamp, as shown and described.

DESCRIPTION

FIG. 1 is a front elevational view of the lamp showing my new design, the rear view being a mirror image thereof;

FIG. 2 is an elevational view of one side of the lamp, the other side being a mirror image thereof;

FIG. 3 is a top plan view thereof; and

FIG. 4 is a bottom plan thereof.
